UNITED STATES PATENT OFFICE

148,192

DESIGN FOR A RADIO RECEIVER OR SIMILAR ARTICLE

Morris J. Simons, New York, N. Y.

Application June 29, 1946, Serial No. 131,163

Term of patent 3½ years

(Cl. D56—4)

To all whom it may concern:

Be it known that I, Morris J. Simons, a citizen of United States, residing at New York city, in the county of Bronx and State of New York, have invented a new, original, and ornamental Design for a Radio Receiver or Similar Article, of which the following is a specification, reference being had to the accompanying drawing, forming part thereof.

In the drawing:

Fig. 1 is a front perspective view of a radio receiver showing my new design; and

Fig. 2 is a rear perspective view thereof.

I claim:

The ornamental design for a radio receiver or similar article, as shown.

MORRIS J. SIMONS.
